COUNTING AND PRINTING MECHANISM

Louis Scher, Shaker Heights, Ohio, assignor to
The Tickometer Company, Cleveland, Ohio, a
corporation of Ohio

Application May 11, 1943, Serial No. 486,497

7 Claims. (Cl. 101—235)

This invention relates to mechanisms for counting and printing paper articles such as coupons, tickets, bank checks and the like and more particularly to an improved mechanism of this kind.

An object of this invention is to provide an improved mechanism of this character in which a printing means is associated with the counting means for printing indicia on the individual articles in succession while they are being advanced and counted, and in which one such printing operation is carried out for each cycle of operation.

Another object of this invention is to provide an improved mechanism of this kind in which the counting and printing means are actuated intermittently and such actuation is controlled in response to the forward movement of the articles through the mechanism.

A further object of this invention is to provide an improved mechanism of this character which will operate in a rapid and highly satisfactory manner and without repeated adjustment even though articles of different sizes are mixed together in the bundle of articles to be fed.

Yet another object of the invention is to provide an improved mechanism of the character referred to wherein the control means which is responsive to the forward movement of the articles is of a novel form enabling the same to cooperate efficiently with different sizes of articles without causing damage to such articles.

The invention may be further briefly summarized as consisting in certain novel arrangement and combinations of parts hereinafter described and particularly set out in the appended claims.

In the accompanying sheets of drawings,

Fig. 1 is a plan view, with portions broken away, of a counting and printing mechanism embodying my invention, the apparatus being viewed as indicated by line 1—1 of Fig. 2;

Fig. 2 is a side elevation thereof looking in the direction of the arrow A of Fig. 1;

Fig. 3 is a partial side elevation looking in the opposite direction as indicated by the arrow B of Fig. 1;

Fig. 4 is a view of the apparatus as seen from the article feeding end as indicated by line 4—4 of Fig. 2;

Fig. 5 is a longitudinal sectional elevation taken through the mechanism as indicated by line 5—5 of Fig. 1;

Fig. 6 is a partial plan view of a portion of the mechanism at the location of the printing means, as indicated by line 6—6 of Fig. 2;

Fig. 7 is a partial longitudinal sectional view taken on line 7—7 of Fig. 6;

Fig. 8 is a partial vertical sectional view taken on line 8—8 of Fig. 1;

Fig. 9 is a similar sectional view but with a longer article in the mechanism;

Fig. 10 is a partial vertical sectional view taken on line 10—10 of Fig. 1;

Fig. 11 is a partial transverse sectional view taken on line 11—11 of Fig. 10;

Fig. 12 is a sectional detail view taken on line 12—12 of Fig. 6 and showing the driving gears for the printing means;

Fig. 13 is a detached edge view of one of the gears shown in Fig. 12;

Fig. 14 is a fragmentary view on a larger scale showing the escapement gears and yoke;

Fig. 15 is an end view of the type wheel of the printing means;

Fig. 16 is a front or edge view of the type wheel;

Fig. 17 is a sectional view through the type wheel taken on line 17—17 of Fig. 15;

Fig. 18 is a view similar to that of Fig. 5 but showing the escapement yoke and stop lever in a different position, and

Fig. 19 is a sectional detail view taken substantially as indicated by line 19—19 of Fig. 7.

The mechanism herein disclosed is of the kind shown in earlier issued U. S. Patents Nos. 1,317,979 and 1,423,333, but embodies certain improvements over the mechanisms of those patents. To the extent that the present mechanism is similar to said earlier patents, it will be described in a general way and the improvement features will be described in greater detail.

As shown in the drawings the mechanism is provided with a frame 10 having article feeding means 11 at one end thereof, and article receiving or stacking means 12 at its other end to which the articles are advanced or conveyed by advancing means located between the feeding and stacking stations. The frame 10 includes upright side members or plates 10a and 10b, in which various shafts of the mechanism are mounted or journaled, and suitably located transverse connecting elements, such as the bars 13 and the inclined plate 14, the latter of which also forms a part of the feeding means 11 and provides a support or table for a pack or group of the articles to be fed. The side plate 10b also

carries a bracket 15 which supports the counting device 16.

The feeding means 11 comprises feed rolls 17 against which the pack of articles to be fed is pressed by a pusher plate 18. This plate slides on the table 14 and is actuated by a swinging lever 19 mounted on the pivot shaft 20 and connected with the pusher plate by the link 21. The spring 22a on the shaft 20 acts to urge the pusher plate 18 toward the feed rolls 17. The feeding means also includes the smaller starting rolls 22 which serve to initiate the downward movement of the topmost article so that its lower edge will be gripped by the larger feed rolls 17

60 to start the movement of such article through

the mechanism between the spaced guide plates 23a and 23b.

Associated with the feeding means is a safety device 24 for preventing the feeding of more than one article at a time through the mechanism which might otherwise result in jamming. This safety device includes a shoe 25 adjacent the feed rolls 17 and spaced therefrom a distance to permit the passage of only one of the articles at a time. The shoe 25 is pivotally connected with a lever 26 which is carried by a rock shaft 27. If two or more of the articles stick together and enter the space between the feed rolls 17 and the shoe 25, they will depress the shoe and rock the shaft 27, and this motion transmitted through the lever 27a and pawl 27b will, in turn, swing a latch finger 28 in a direction to release a brake finger 29. The release of the finger 29 will result in the setting of a brake device 30 which cooperates with a flange 31 on the shaft 32 carrying the feed rolls 17. The setting of the brake device 30 will hold the shaft 32 and the feed rolls 17 against further rotation until the jammed condition has been cleared and the brake device reset. This brake device is similar to the brake device disclosed in said earlier patents and need not be described in greater detail.

The stacking means 12 may comprise an inclined support or bracket 33 connected with the frame 10 and a movable shoe 34 which is slideable on such bracket. As the articles are delivered to the stacking device 12, they move under the shoe 34 which serves to hold the articles in place while the stack is being formed. Each succeeding article moves into position beneath the previously stacked ones.

During their travel from the feeding means 11 to the stacking means 12, the articles are advanced by feed rollers or groups of feed rollers designated 35, 36, 37 and 38. If desired, endless belts 39 may be arranged to pass over these rollers so that the articles can be supported continuously during their advance movement, particularly when articles of relatively narrow width are being fed. The rollers 36 and 37 are carried respectively by positively driven shafts 40 and 41 and the rollers 35 and 38 are carried respectively by idler shafts 42 and 43 and are driven from the rollers 36 and 37 by the belts 39. Pressure rollers 44a and 44b carried by a transverse supporting bar 44 cooperate respectively with feed rolls 36 and 37 for pressing the articles against the latter. The rolls 36 are driven at a higher surface speed than the feed rolls 17 and as soon as an article reaches the rolls 36 its forward movement is speeded up relative to the next following article which is still held by the rolls 17. This results in a desired separation or spacing between successive articles.

The mechanism can be driven from any suitable source of power as by means of a belt 45 extending around a pulley 46 mounted on a transverse shaft 47. The shaft 47 carries a gear 48 which meshes with an idler gear 49 and with a gear 50 which is connected with the shaft 32 through a friction clutch 51. The shaft 32 also carries a gear 52 which drives a gear 53 through idler gears 54 and 55, the latter gears being carried by an idler shaft 56. The gear 53 is mounted on and drives the shaft 57 which carries the starting rolls 22. The transverse shafts 40 and 41 on which the rollers 36 and 37 are mounted, respectively, carry gears 58 and 59 which mesh with an idler gear 60. The idler

gear 60 is connected with the idler gear 49 by the idler shaft 61 so that the shafts 40 and 41 will be rotated in the same direction while being driven from the shaft 47.

5 The friction clutch 51 which connects the gear 50 with the shaft 32 provides a slip connection which will permit the gear 50 to rotate idly on the shaft 32 during such time as the brake device 30 holds this shaft against rotation.

15 The forward movement of the articles through the mechanism is utilized to initiate and control the actuation of the counter 16 so that an accurate count of the individual articles will be obtained even though they are moved through the mechanism at a relatively rapid rate. As mentioned above I provide a printing means 62 in the present mechanism which is associated with the counting means so that the operation of both the counting means and the printing means will be controlled by the forward movement of the individual articles.

20 In the accomplishment of this control function, I provide an escapement mechanism 63 having a rotary trip device 64 associated therewith. The escapement mechanism includes escapement gears 65 and 66 of which the gear 66 has two diametrically opposed flats or blank spots 66a and is of the form known as a "mutilated" gear. The gear 65 is a continuously driven gear but the mutilated gear 66 is driven intermittently as will be presently explained. The gear 65 is mounted on a shaft 67 of which the inner end is carried by a pivoted arm 68. A spring 69 acts on the arm 68 and urges the latter in a direction tending to shift the gear 65 toward the gear 66. The shaft 67 extends through the side plate 10b and its outer end carries a pinion 67a which meshes with a gear 47a carried by the continuously driven shaft 47.

25 The mutilated gear 66 is carried by an escapement shaft 70 which extends through the side plate 10b of the frame and carries a pinion 71 which meshes with and drives the gear 72 of the counter 16. The inner end of the shaft 70 also carries a cam 73 which is connected with the mutilated gear 66 and has diametrically opposed cam fingers 74. The escapement mechanism also includes a short rock shaft 75 which carries an escapement yoke 76 and a stop lever 77. The escapement yoke 76 straddles the cam 73 and has arms 76a and 76b which cooperate with the cam fingers 74. The escapement yoke 76 is oscillated by the cam 73 and at the same time controls the rotation of this cam so that the shaft 70 will be intermittently rotated one-half revolution at a time by motion imparted to the mutilated gear 66 from the continuously rotating gear 65. This intermittent rotation of the shaft 70 through a half revolution at a time causes the counter 16 to be positively driven so that each half revolution of the shaft 70 increases the reading of the counter by one number. This cooperation of the escapement yoke 76 with the cam 73 also causes actuation of the stop lever 77 for controlling the intermittent actuation of the printing means 62, as will be presently explained more in detail.

30 The rotary trip device 64 which, as mentioned above, is carried by the same shaft (shaft 70) that carries the mutilated gear 66 and the cam 73, is provided with trip fingers 80 which extend into the path of forward movement of the articles being advanced and are adapted to be engaged in succession by the leading edges of the successively fed articles. Upon engagement of an ar-

title with one of the trip fingers 80, the article causes rotation to be imparted to the shaft 70 which shifts the mutilated gear 66 enough to move one of the blank spots 66a thereof out of a position of tangency with the gear 65 and to thereby bring one or more of the teeth of the mutilated gear into mesh with the teeth of the gear 65 (see Fig. 18). The gear 66 is thereupon rotated through a half revolution by the gear 65 to bring the other blank spot into a position of tangency with the gear 65, whereupon the gear 66 again comes to rest.

Each time that the gear 66 is thus rotated through a half revolution, the cam 73 is also rotated for a half revolution and imparts a 15 rocking oscillation to the yoke 76. This oscillation of the yoke causes the latch lever 77 to be lifted to release the stop cam 97 of the printing means. The operation of the mechanism is such that the article, which actuates one of the trip fingers 80 to bring about actuation of the counter 16 and oscillation of the escapement yoke 76, will arrive at the printing means 62 in timed relation to the release thereof by the stop lever 77 so that the article which has initiated a cycle 20 of operation of the printing means will have indicia printed thereon during that cycle.

The present mechanism embodies an improved construction for the trip fingers 80 and a guard 81 which enable the mechanism to successfully handle articles of varying width without jamming and without damage to the articles even though such articles are mixed together in the same pack. The guard 81 comprises a plate or strip which is hinged on a pivot pin 82 and over which the articles pass during their advance movement. The guard 81 extends in the direction of the forward movement of the articles and its free end is located above and adjacent the trip device 64 (see Figs. 8 and 9).

The trip fingers 80 are carried by a plate or bar 83 which is mounted on the shaft 70 and each trip finger is supported at an intermediate point thereof by a pivot 84. The inner ends of the trip fingers 80 lie on opposite sides of the shaft 70 and are yieldingly drawn toward each other by a tension spring 85 connected therewith. The outer ends of the fingers 80 engage the under side of the guard 81 in succession during the intermittent rotation of the shaft 70. When relatively narrow articles T¹ are being fed, as shown in Fig. 8, the guard 81 is relatively ineffective and readily swings upwardly to permit the fingers 80 to move past the same to a position for engagement by the successively fed articles. When relatively wide articles T² are being fed, as shown in Fig. 9, the article which is passing the trip station overlies the guard 81 which then prevents the finger 80 from moving to the article-engaging position until the trailing edge of the article T² has traveled past the guard. While the trip finger remains under the guard it is prevented from contacting the moving article. This is desirable because imperfections or irregularities of the article might otherwise strike the trip finger and cause premature actuation of the escapement mechanism. The use of the guard 81 and the yieldably mounted trip fingers 80, enable the mechanism to successfully handle different widths of articles even though they are intermixed and the need for any adjustments in the mechanism to accommodate the same to such different widths of articles.

In addition to the pinion 71 the outer end of the shaft 70 carries a collar 70a having diametrical

opposed notches 70b in which a detent 70c engages. The cooperation of the detent 70c with the collar 70a holds the shaft 70 against backward rotation which would prevent proper functioning of the escapement mechanism. Such backward rotation of the shaft 70 might be caused by one of the cam fingers 73 rebounding away from the stop arm 76a of the escapement device 76 or by the spring 85 of the rotary trip device reacting against the guard 81.

One side of the notches 70b is relatively inclined so as to cause the detent to be readily lifted when the shaft 70 is rotated in its forward direction.

The printing means 62 includes a platen roller 88 mounted on the shaft 41, and a type wheel 89 cooperating therewith. The wheel 89 carries type or other indicia elements 90, and one or more blank elements or spacers 90a which are lower in height than the elements 90. The type wheel is carried by a shaft 91 which is journaled in an arm 92 of a bracket or body 93 which can be suitably attached to the transverse supporting bar 44. The body 93 supports the type wheel 89 with the plain portion of the surface thereof, which is formed by the spacers 90a, spaced slightly from the periphery of the platen 88 so that the latter can rotate out of contact with the surface of the type wheel until a printing operation has been initiated. As shown in the drawings, the tops of the indicia elements 90 extend somewhat above the periphery or plain portion of the type wheel and, when the type wheel has been rotated a predetermined extent to initiate 30 the printing operation, one end of the series of indicia elements comes into contact with the periphery of the platen 88 and thereupon the type wheel will be driven by the frictional engagement of the indicia elements with the platen. 35

As the article which has tripped the escapement mechanism to thus initiate the counting and printing operations, passes between the type wheel 89 and the platen 88 the indicia represented by the elements 90 will be printed 40 thereon.

The shaft 91 of the printing device also carries a gear 96 and a stop cam 97. The gear 96 meshes with a driving gear 98 carried by the continuously rotating shaft 41. The gear 98 is not keyed to the shaft 41 but is connected therewith through friction clutch means 99 which will permit the gear 98 to remain stationary when the stop cam 97 is held against rotation by the stop lever 77. When this stop lever is lifted by the escapement yoke 76 so as to release the cam 97 (see Fig. 18), the gear 98 rotates with the shaft 41 and drives the type wheel through the gear 96 and the shaft 91. The gear 98 imparts initial rotation to the type wheel to cause the above-mentioned frictional engagement of the indicia elements 90 with the platen 88 to take place. The gear 98 assists in driving the type wheel during such frictional engagement of the indicia elements with the platen 88 and thereafter continues to rotate the type wheel to the extent permitted by the stop lever 77 and thereby returns the type wheel to its starting position. Immediately after the cam 97 has been released by the stop lever 77, as just explained, the arm 76b of the yoke 76 is disengaged by the cam finger 74. The stop lever 77 then rides on the top of the stop cam 97 but as soon as the cam passes the stop lever the latter will be pulled down by the spring 100 to a position in which it will be engaged by the cam 97 and the type wheel will 75

thereby be prevented from making more than one revolution per cycle of operation.

The printing means 62 may also include an inking roller 101 which is supported above the type wheel by an arm 102 so that the roller will contact the indicia elements and supply ink thereto. The pressure of the inking roller on the type wheel can be varied by means of a screw 103 having its grooved inner end anchored by the pin 104 and which screw has thread engagement with the arm 102 and can be rotated to swing the arm toward or away from the type wheel. A spring-pressed friction element 105 (see Fig. 19) made of leather or other suitable material, serves to hold the screw 103 against accidental turning.

As shown in Fig. 4, the shaft 32 can be provided with an extension on which a hand wheel or knob 106 is mounted. Whenever two or more articles simultaneously enter the space between the feed rolls 17 and the shoe 25 the brake device 30 is tripped and locks the shaft 32 against rotation, as previously explained, while other portions of the mechanism continue to run. To release the jammed articles it is necessary to rotate the feed rolls 17 in a reverse direction and it is for this purpose that the knob 106 is provided.

Although the printing means 62 is described as a part of the general mechanism, such printing means can be readily detached and the mechanism operated successfully as an article counting means.

From the foregoing description and accompanying drawings it will now be readily understood that I have provided an improved mechanism for counting and printing coupons, tickets, bank checks or other paper articles in a rapid and satisfactory manner.

While I have illustrated and described my improved mechanism in considerable detail, I desire it to be understood that I do not wish to be correspondingly limited but regard my invention as including all modifications and variations coming within the scope of the appended claims.

Having thus described my invention, I claim:

1. In a machine of the character described, means for advancing coupons or the like in succession through the machine, a continuously driven toothed rotary member, a device adapted to be intermittently driven for the performance of a desired function in connection with said coupons, means for driving said device including a rotary member having interrupted teeth for intermittently connecting such second rotary member with the first rotary member, and a spring biased finger pivotally carried by the second rotary member and adapted to be engaged by the coupons being advanced for controlling the connection between the first and second rotary members.

2. In a machine of the character described, means for advancing coupons or the like in succession through the machine, a continuously driven rotary member, a device adapted to be intermittently driven for the performance of a desired function in connection with said coupons, means for driving said device including a rotary member having means for intermittently connecting such second rotary member so as to be driven by the first rotary member, trip means yieldably carried by the second rotary member and adapted to be engaged by the coupons being advanced for controlling the connection between the first and second rotary members, and means preventing said trip means from moving to a coupon-engaging position until the preceding coupon has been advanced a predetermined extent.

advanced for controlling the connection between the first and second rotary members, and means preventing said trip means from moving to a coupon-engaging position until the preceding coupon has been advanced a predetermined extent.

3. In a machine of the character described, means for advancing coupons or the like in succession through the machine, a device adapted to be intermittently driven for the performance of a desired function in connection with said coupons while they are being advanced, means for driving said device intermittently, rotary trip means controlling the intermittent actuation of said device and having yieldably mounted fingers thereon adapted to be engaged in succession by the leading edges of the successively fed coupons, and a guard over which said coupons move and which is located relative to said rotary trip means so as to prevent movement of said fingers to a coupon-engaging position until the preceding coupon has been advanced beyond the guard.

4. In a feeding mechanism for a machine of the character described, means for advancing coupons or the like in succession, a guard over which said coupons travel, and a rotary trip device having a yieldable finger thereon for cooperation with the successive coupons being advanced and engageable with the underside of said guard, the length of said guard and its location with respect to the path of travel of said finger being such as to prevent the finger from moving to a position to be engaged by one coupon until the preceding coupon has advanced beyond the guard.

5. In a feeding mechanism for a machine of the character described, means for advancing coupons or the like in succession, a pivoted guard over which said coupons travel in a direction from the pivot toward the free end thereof, and a rotary trip device having a yieldable finger thereon engageable with the underside of the guard and adapted to be released by said free end for movement to a coupon-engaging position.

6. In a feeding mechanism for a machine of the character described, means for advancing coupons or the like in succession, a movable guard over which said coupons travel, and a rotary trip device having outwardly extending pivoted fingers thereon successively engageable with the underside of said guard and adapted to be released thereby for movement to a coupon-engaging position, said trip device having a stop thereon and the inner ends of said fingers being yieldingly held against said stop by a tension spring.

7. In a machine of the character described, means for advancing coupons or the like in succession through the machine, a continuously driven rotary member, a register, a second rotary member adapted to actuate said register and having means for intermittently connecting such second rotary member so as to be driven by the first rotary member, trip means yieldably carried by the second rotary member and adapted to be engaged by the coupons being advanced for controlling the connection between the first and second rotary members, and means preventing said trip means from moving to a coupon-engaging position until the preceding coupon has been advanced a predetermined extent.

LOUIS SCHER.
